UNITED STATES PATENT OFFICE.

ERNEST MILLER LUNT, OF NAPERVILLE, ILLINOIS, ASSIGNOR TO TOWLE MANUFACTURING COMPANY, OF NEWBURYPORT, MASSACHUSETTS, A CORPORATION OF MASSACHUSETTS.

DESIGN FOR A DINNER-SET CABINET.

42,187.

Specification for Design.

Patented Feb. 20, 1912.

Application filed November 11, 1911. Serial No. 659,834. Term of patent 7 years.

To all whom it may concern:

Be it known that I, ERNEST MILLER LUNT, a citizen of the United States, residing at Naperville, in the county of Dupage and State of Illinois, have invented a new, original, and ornamental Design for Dinner-Set Cabinets, of which the following is a specification, reference being had to the accompanying drawing, forming a part thereof.

The figure is an exterior view in perspec-

tive of a dinner set cabinet showing my new design.

I claim:

The ornamental design for a dinner set cabinet, as shown.

ERNEST MILLER LUNT.
